UNITED STATES PATENT OFFICE.

ANTHONY CAMINETTI, JR., OF SAN FRANCISCO, CALIFORNIA.

SPOTLIGHT.

Application filed October 6, 1925. Serial No. 60,857.

My invention relates to new and useful improvements in vehicle lights and more particularly to what may be termed a spotlight, the principal object of the invention residing in the provision of a device of this character which may be supported upon the forward part of the vehicle and the rays of light projected both horizontally and vertically, the spotlight being held in its adjusted positions to throw the light rays uniformly along the road.

Another object of the invention resides in the provision of a spotlight of the character described which is adjustable by means of a lever or handle positioned upon the instrument board of the vehicle within easy reach of the operator.

A further object of the invention resides in the provision of a spotlight which is adjustable both horizontally and vertically, means being provided to lock the spotlight against vertical adjustment to conform with the laws of those communities which prohibit the vertical adjustment of a vehicle light.

Still another object consists in the provision of a novel form of clutch which is normally set to either adjust the spotlight horizontally or vertically when the operating mechanism is manipulated but which is adapted to be moved into another direction to allow the other adjustment of the spotlight.

As a further object of the invention I provide a novel form of support or bracket whereby the spotlight may be secured to a suitable part of the vehicle such as the filling thimble or opening of an automobile radiator or the radiator shell.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings:

Fig. 1 is a top plan with parts broken away and parts shown in horizontal section, 55 Fig. 2 is a side elevation with parts shown in longitudinal vertical section.

Fig. 3 is a horizontal section on the line 3—3 of Fig. 2 with parts shown in top plan.

Fig. 4 is a side elevation of my improved 60 form of light and supporting bracket secured to the radiator of an automobile.

Fig. 5 is a front elevation of the light secured to the automobile radiator.

Fig. 6 is a front elevation of the light 65 with parts shown in transverse vertical section.

Fig. 7 is a horizontal section on the line 7—7 of Fig. 2.

Fig. 8 is a detail showing a horizontal 70 section on the same line as 3—3 of Fig. 2 showing the manner of connecting the operating wire or cable to the gear pulley.

Fig. 9 is a vertical section on the line 9—9 of Fig. 3 and 75

Fig. 10 is a detail showing an inner face view of the lower end of the supporting yoke for the light.

Drivers of automobiles will readily appreciate the difficulty in driving during the night, particularly on country roads and through hilly country where the automobile lights are permanently adjusted and I have provided my improved form of adjustable light so that an operator may set the light 85 to the side of the road and may vertically adjust the same so as to hit the road at the desired distance in front of the vehicle. When so adjusted the lamp will be fixed to throw the light or rays at a uniform position 90 relative to the vehicle and the light rays can be made to follow the road when going up or down hill or when rounding a curve. It will be appreciated that the lamp may be so adjusted to the right hand side 95

of the road so that the operator of the vehicle can easily see the side edge of the road and be guided so that he will not run off of the road. Very often the ordinary headlights of an approaching vehicle will 100 blind an operator driving in the opposite direction and he will run off the side of the road thereby causing an accident and with my improved form of adjustable lamp this will be overcome. At the same time the 105 laws of some States require that when approaching another vehicle that headlights be dimmed and then it is impossible to clearly view the road. With my improved form of lamp the road is always clear and 110 the light adjusted so as not to shine into the face of an approaching driver. Some

State laws also prevent the vertical adjustment of a vehicle light and to provide for this I have provided means whereby the lamp may be locked or held against vertical adjustment although allowing the same to be readily adjusted horizontally.

In the drawings 1 indicates the shell surrounding the cooling radiator of an automobile and through which the thimble 2 surrounding the water filling opening extends, the opening being closed by means of the cap 3. The usual headlights are shown at 4 mounted on each side of the vehicle in front of the radiator.

15 My improved form of spotlight is adapted to be positioned in front of the radiator between the headlights 4 and is supported by means of a bracket which is secured to the thimble surrounding the filling opening. 20 Secured around the thimble 2 by means of the screws 5 or other suitable fasteners is a two part clamping ring shown generally at 6 and rotatably carried by the ring are the eyes 7 to which are secured a plate 8, bolts 25 extending from the rear end of said plate and passing through the eyes 7 for receiving the securing nuts 9. Spacing sleeves or washers 10 are received on the bolts of the plate and space the end of the plate from the eyes 7 as more particularly illustrated in Fig. 1 of the drawings. Formed on the plate and depending therefrom, adjacent the outer end, are the transversely spaced lugs 11 to which is secured a brace 12, the upper end of the brace being forked as shown at 13 and the lower end forked as shown at 14. The arms of the forked end 14 have the plates 15 pivotally connected thereto at 16 and these plates 15 engage the front face 30 of the radiator shell and are secured thereto by means of the bolts 17 which pass through the radiator shell and receive the nuts 18 which engage the inner face of the radiator shell front. Preferably the brace 12 is formed in two sections as more particularly illustrated in Fig. 2 connected together by means of the threaded coupling shown generally at 19.

50 Suspended from the outer end of the plate 8 is my improved form of spotlight. An upwardly extending flange 20 is formed integrally with the end of the plate 8 and is exteriorly threaded to receive the cap 21. An opening 22 is formed in the plate 8, 55 within the confines of the flange 20 and through this opening extends a sleeve 23 which has the elongated oppositely disposed openings 24 for a purpose which will be later described. The upper end of the sleeve 23 is exteriorly threaded to receive the nut 25 and the lock nut 26, the nut 25 being of greater diameter than the nut 26 and being mounted on the ball bearing ring 27 as more particularly illustrated in Figs. 2 60 and 6. The sleeve 23 is thus rotatably sup-

ported in the arm 8. The lower end of the sleeve 23 is provided with the outwardly extending flange 28 and carried by this flange and secured thereto is the forked yoke 29 between the depending arms of which is pivotally mounted, for swinging movement, the light housing or casing 30. A ring or housing 31 is interposed between the bottom surface of the plate 8 and the top of the yoke 28 as more particularly shown in Fig. 2 and formed on the upper surface of the top portion of the yoke is the circular flange 32 within which is received the ballbearing ring 33 supporting the ring or housing 31 which in turn supports the horizontally disposed gear wheel 34 which has the pulley 35 formed integrally on its under surface. Extending upwardly from the upper face of the gear 34 is the pin 36 for the purpose which will be later described. The upper 80 surface of the gear has the depressed portion shown more particularly in Fig. 2 and the pin 36 is received in this depressed portion. As is quite clearly shown the gear and its pulley are rotatably mounted around the sleeve 23.

Slidably mounted around the sleeve 23 is the sleeve 37 on the upper end of which is formed the outwardly extending flange 38 the edge of which is beveled as shown more 95 particularly in Fig. 2. A pin 39 extends transversely through the sleeve 37 and the elongated openings 24 so that the said sleeve 37 is vertically adjustable upon the sleeve 23 and may rotate therewith. Formed in the lower end of the sleeve 37 are the circumferentially spaced recesses 40 which when the sleeve is in its lowermost position are adapted to receive the pin 36 carried by the gear 34. When lowered the sleeve 37 is connected to the gear 34 by the pin 36 being received in one of the recesses 40 and is rotatable therewith. The sleeve 37 is normally held in its lowered position by means of the coiled spring 41 as more particularly 100 illustrated in Figs. 2 and 6 of the drawings. 105

Carried by the pin 39 is the bolt 42 having the transversely extending rib 43 formed on its lower end, this rib 43 being adapted to engage the teeth 44 of the segment 45 formed on or secured to the top of the light housing or casing 30. The rib will engage the teeth of the segment when the sleeve 37 is in its lowermost position. Recesses 46 are formed in the outer face of the sleeve 37 for a purpose which will be later described.

Supported in the bearing 47 formed on the ring or housing 31 is the shaft 48 having the reduced pointed extension 49 formed on the inner end thereof. A beveled gear 50 is carried by the shaft 48, adjacent the inner end thereof, and meshes with the gear 34. The segmental wedge shaped member 51 is carried by the reduced extension 49, as more particularly illustrated in Figs. 2 and 7, in 115 120 125 130

position to engage the beveled flange 38 of the sleeve 37 when the shaft 48 is manipulated in a manner to be later described to raise the sleeve 37 and disengage the pin 36 5 from its recess 40 thereby allowing the rotation of the gear 34 independently of the sleeve 37.

Connected to the opposite end of the rod 48, by the universal joint 52, is the rod 53 10 which passes through the radiator shell 1 as shown more particularly in Fig. 1, beneath the engine hood and through the instrument board 54 being rotatably and slidably mounted in the instrument board through 15 the bearing 55 as shown more particularly in Fig. 3 of the drawings. Universal joints 52' will be positioned in the rod 53 as desired for allowing the proper positioning of the rod through the instrument board. The bearing 55 has the exteriorly threaded extension 56 to receive the nut 57 and the rod 53 is threaded intermediate its ends as shown at 58 to receive the nut 59. An enlargement 60 is formed on the rod 53, on the 20 opposite side of the instrument board 54 to which the nut 59 is positioned the nut 59 and enlargement 60 limiting the slidable movement of the rod in opposite directions. A handle 61 is formed on the inner end of the 25 rod 53 and is positioned relative to the instrument board in such a manner that it is within easy reach of the operator of the vehicle.

The pulley 35 formed on the gear 34 has 30 the hole 62 more particularly illustrated in Figs. 3 and 8 of the drawings through which wire 63 is threaded and encircling the pulley is the wire or cable 63 having the ends 64 extending in opposite directions as shown more particularly in Figs. 3 and 8 and passing 40 through openings 65 formed in the arms of the yoke 29 as more particularly shown in Fig. 6 of the drawings. The wire 63 is held in the hole 62 by a set screw 62'. As 45 has been previously stated the light housing 30 is pivotally mounted between the arms of the yoke 29 so that it may be swung vertically. The light housing 30 is secured to the shafts 66 as shown more particularly in Fig. 50 6 by means of the screws or bolts 67 the outer ends of these shafts being enlarged as shown at 68 and rotatably mounted in recesses formed in the outer faces of the arms of the yoke 29. The enlargements 68 are 55 formed with the circumferentially extending groove 69 in which are received the ends 64 of the wire or cable 63 these ends of the wire or cable being secured to the shafts and enlargements thereof by means of a set screw as shown at 70 more particularly in Fig. 9 the set screw being inserted through the center bore of the shaft 66. When the wire 60 is drawn upon rotation of the pulley 34 it will rotate the shafts 66 and thereby swing 65 the light housing or casing vertically.

Semi-circular openings 71 are formed in the arms of the yoke 28 adjacent the lower ends thereof in order to limit the vertical motion of lamp housing, a pin 71' extending from the arm of the yoke into the opening 71.

As shown more particularly in Fig. 2 an exteriorly threaded rod 72 extends through the cap 21 and the upper end of the sleeve 23 and when in its lowermost position is 75 adapted to engage the upper end of the bolt 42 to lock the same in its lowermost position. This rod 72 is recessed in its upper end to receive the removable key 73 by means of which it may be rotated. The purpose of this rod 72 will be more fully brought out in the following description. The lamp housing receives a parabolic reflector which carries an electric light bulb connected with a flexible wire extending 80 back to a source of electricity, not shown, in the automobile.

Having fully described the detailed construction of my spotlight I will now describe more fully the operation. The parts will 90 normally be in position shown in Fig. 2, and when the operator of the vehicle desires to swing the light horizontally he grasps the handle 61 and rotates the shaft 53. This in turn rotates the shaft 48 and the beveled 95 gear 50, the beveled gear 50 meshing with the gear 34 rotating said gear 34. The sleeve 37 is in its lowermost position and the pin 36 being received in one of the recesses 40 the sleeve 37 will rotate with the gear 100 34 and as the pin 39 passes through the openings 24 will in turn rotate the sleeve 23 and the bolt 42 thus swinging the yoke 28 horizontally as the rib 43 is engaged with the teeth 44 of the segment 45. Should it be 105 desired to swing the light housing 30 vertically the handle 61 is grasped and the rod 53 slid longitudinally so that the member 51 will engage the beveled flange 38 and raise the sleeve 37 thereby disengaging the 110 pin 36 from its recess 40. The raising of the sleeve 37 also raises the bolt 42 to disengage the rib 43 from the teeth 44. With the parts in the position just described the shafts 53 and 48 are then rotated and the gear 50 115 meshing with the gear 34 will rotate the gear 34 independently of the sleeve 37 and as the wire or cable 63 is connected to the pulley 35 the ends of said wire or cable will draw on the enlargements 68 and rotate the 120 shafts 66 and thereby swing the light housing 30 upwardly and downwardly according to the direction of the rotation of the shafts. The light may be held in its vertically adjusted position by drawing the shafts rearwardly so that the bolt 42 may be lowered to engage its rib 43 with the teeth 44.

In some States or communities there are laws prohibiting the adjustment of such lights vertically. When there are such laws 130

my light may be locked against vertical adjustment by screwing the rod or bolt 72 downwardly so that the lower end engages the top of the bolt 42. When thus lowered it will be appreciated that the sleeve 37 and the bolt 42 carried thereby cannot be raised to position the parts for operation to swing the light vertically. The rod or bolt 72 is rotated by the key 73 and when in its locking position cannot be tampered with by an unauthorized person for it will be understood that the key will be removed by the owner or operator of the vehicle.

From the above description it will be seen that I have provided a novel form of spotlight which may be swung both horizontally and vertically through manipulation of the same handle which is in easy reach of the operator. At the same time the light may be easily connected or disconnected from the vehicle and is of such a construction as to present a neat and pleasing appearance to the eye.

When the rods are slid inwardly for vertically swinging the spotlight the pointed extension 49 will be received in one of the recesses 46 of the sleeve 37 and thereby hold it against rotation.

Certain features of my invention herein disclosed and not claimed are included in claims constituting the subject matter of my copending application Serial No. 145,826, filed November 2, 1926.

Having fully described my invention what I claim as new and desire to secure by Letters Patent is:

1. A light of the character described adapted to be connected to a vehicle, including a support, a yoke carried by the support and adapted for horizontal swinging movement, a housing mounted in the yoke and adapted for vertical swinging movement, a sliding bolt engageable with housing for normally holding the same against vertical swinging movement, means for releasing the sliding bolt, and means for imparting the swinging movements to the housing and yoke.

2. A light of the character described adapted to be connected to a vehicle, including a support, a yoke carried by the support and adapted for horizontal swinging movement, a housing mounted in the yoke and adapted for vertical swinging movement, a toothed rack carried by the housing, a sliding bolt engageable with the rack for normally holding the housing against vertical swinging movement, means for releasing the sliding bolt from the rack, and means for imparting the swinging movements to the housing and yoke.

3. A light of the character described adapted to be connected to a vehicle, including a support, a yoke carried by the support and adapted for horizontal swinging

movement, a housing mounted in the yoke and adapted for vertical swinging movement; means engageable with the housing for normally holding the same against vertical swinging movement, and a rotatable and slid able member for swinging the housing and yoke, said member when rotated with the holding means engaged with the housing swinging the yoke horizontally and when slid to release the holding means and then rotated swinging the housing vertically.

4. In combination with an automobile having a radiator and a filling opening therefor, a shell surrounding the radiator, a support connected to the radiator filling opening, a light housing connected to the support, a brace extending from the support, plates pivotally connected to the brace, nuts positioned interiorly of the radiator shell, and bolts passing through the pivoted plates and the radiator shell and engageable with the nut.

5. A spotlight of the character described adapted to be connected to a vehicle, a support, a yoke carried by the support for horizontal swinging movement, a light housing carried by the yoke for vertical swinging movement, a gear, a sleeve normally engageable with the gear for rotation therewith, means for rotating the gear and sleeve for swinging the yoke horizontally, and means for disengaging the sleeve from the gear whereby upon rotation of the gear the spotlight will be swung vertically.

6. A spotlight of the character described adapted to be connected to a vehicle, a support, a yoke carried by the support for horizontal swinging movement, a light housing carried by the yoke for vertical swinging movement, a gear, a slid able sleeve normally engageable with the gear for rotation therewith, means for rotating the gear and sleeve for swinging the yoke horizontally, and means for sliding the sleeve and disengaging it from the gear whereby upon rotation of the gear the light housing will be swung vertically.

7. A spotlight of the character described adapted to be connected to a vehicle including a support, a yoke carried by the support for horizontal swinging movement, a light housing carried by the yoke for vertical swinging movement, a gear, a slid able sleeve normally engaged with the gear and rotatable therewith, a rotatable and slid able rod, means carried by the rod and engageable with the gear for rotating the gear and sleeve for swinging the yoke horizontally when the rod is rotated, and means carried by the rod and engageable with the sleeve for disengaging the sleeve from the gear when the rod is slid, to allow swinging movement of the light housing vertically upon rotation of the rod.

8. A light of the character described comprising an arm adapted at one end to clamp about the radiator cap of an automobile, a yoke suspended downwardly from and pivoted on a substantially vertical axis to the other end of said arm, a light casing horizontally pivoted within the yoke, and mechanism and connections adapted to be actuated by one movement from within the automobile to adjust the yoke about its axis and by another movement to adjust the light about its axis.

9. A lamp bracket adapted to clamp at one end about the cap of an automobile radiator and having a yoke depending from the other end, a lamp pivoted on a horizontal axis within the yoke, pivotal means having a vertical axis of movement between the yoke and said last mentioned bracket end, 20 and an angular strut member fixed between the ends of the bracket and extending downwardly and rearwardly and adapted to be

fixed to the front of an automobile radiator.

10. A lamp bracket adapted to clamp at one end about the cap of an automobile radiator and having a yoke depending from its other end, a lamp pivoted on a horizontal axis within the yoke, pivotal means having a vertical axis of movement between the yoke and the last mentioned bracket end, an 25 angular strut member fixed between the ends of the bracket and extending downwardly and rearwardly and adapted to be fixed to the front of an automobile radiator, in combination with means adapted to swing the, 30 lamp on said horizontal axis, and mechanism adapted to independently swing the yoke about the vertical axis, and a handle member adapted to selectively operate the 35 said means on said mechanism. 40

In testimony whereof I hereunto affix my signature.

ANTHONY CAMINETTI, Jr.
